UNITED STATES PATENT OFFICE.

FLORIAN BERTRAM PEDERSEN AND HANS PETER ANDERSEN, OF ALAMEDA,
CALIFORNIA.

TOBACCO-DISPENSING DEVICE.

Application filed September 18, 1925. Serial No. 57,237.

This invention relates to improvements in tobacco dispensing devices and has particular reference to a box to accommodate therein tobacco and matches.

5 The principal object of this invention is to produce a smoker's appliance which will be compact, and therefore easily transportable in the pocket of the user.

Another object of this invention is to produce a tobacco box which will contain all the requisites necessary to the rolling of cigarettes such as tobacco, papers and matches.

10 A still further object of this invention is to produce a device of this character which is simple in construction and therefore cheap to manufacture.

15 Other objects and advantages will be apparent during the course of the following 20 description.

In the accompanying drawings forming a part of this specification and in which like numerals are employed to designate like parts throughout the same,

25 Figure 1 is a side elevation of our improved can partly broken away,

Figure 2 is an enlarged fragmentary vertical cross section showing the match dispensing mechanism,

30 Figure 3 is a cross section taken on the line 3—3 of Figure 2,

Figure 4 is a cross section taken on the line 4—4 of Figure 2,

35 Figure 5 is a cross section taken on the line 5—5 of Figure 2,

Figure 6 is a fragmentary detail view showing the spring arrangement for dispensing one match at each operation, and

40 Figure 7 is a fragmentary detail view showing the arrangement of the movable bottom.

It has been common to employ a bag of tobacco and a package of papers and also a box of matches as separate units. It often occurs that the user of these articles forgets or mislays one of them with the result that he is inconvenienced.

45 We have, therefore, devised a can which will have these three essentials handy at all times, and, therefore, the user will be assured of all the requisites of a smoke.

50 In the accompanying drawings wherein for the purpose of illustration is shown a preferred embodiment of our invention, the 55 numeral 5 designates a receptacle having a

movable bottom 6. This bottom is adapted to support a back 7 within which tobacco is placed.

Spring arms 8 are attached to the sides of the bottom 6 (see Figure 7) and carry 60 ball-like lugs 9 adapted to enter openings 11 formed in the side of the container 5, the result being that the bottom 6 may be moved upwardly within the receptacle as the tobacco in the bag 7 is used. 65

At 12 we have shown a cover hinged to the receptacle 5 as shown at 13. This cover has a hinged door 14, through which cigarette papers 16 may be placed upon a shelf 17. 70

In the space above the papers 16, we provide a U-shaped passage 18 within which a plurality of matches 19 are placed. This passage 18 has an opening 21 communicating with the outside of the cover 12. At 75 22 we have shown a ratchet wheel secured to a spindle 23 upon which is wound a web 24. This web extends through the passage 18 and has a follower 26 secured thereto.

The result of this construction is that as 80 the ratchet wheel 22 is rotated in the direction of the arrow of Figure 2, the reeling of the web 24 upon the spindle 23 will cause the matches 18 to be ejected through the opening 21 due to the fact that the ball 85 26 is pushing upon the last match in the passage.

In order to prevent more than one match being dispensed at a time, we provide retaining springs 27 and 28 adjacent the opening 21. 90

At 29 we have shown a lug secured upon the inner surface of the receptacle 5, the tip of which is adapted to contact one of the teeth of the ratchet 22 each time the box 95 is opened and closed. This will result in the ratchet being stepped forward one step at each opening and closing operation and in order to prevent retrograde movement of the ratchet we have placed a spring dependent 31 in the cover 12. 100

It will thus be seen that we have provided a very simple and efficient device and one which will accomplish all of the objects above set forth. 105

It is to be understood that the form of our invention herewith shown and described is to be taken as a preferred example of the same, and that various changes in the shape, size and arrangement of parts may be re- 110

sorted to without departing from the spirit of the invention or the scope of the subjoined claim.

Having thus described our invention, we claim:

In a device of the character described, a receptacle, a cover for said receptacle, a passage within said cover and adapted to maintain a plurality of matches in parallel alignment, means for moving said matches

throughout said passage, a bottom positioned within said receptacle, means for movably holding said bottom within said receptacle, and means for dispensing said matches one at a time as said cover is opened and closed. 15

In testimony whereof we affix our signatures.

FLORIAN BERTRAM PEDERSEN.
HANS PETER ANDERSEN.
